UNITED STATES PATENT OFFICE.

HENRY A. HEATH, OF URBANNA, AND JAMES E. GRAY, OF SALUDA, VIRGINIA.

FOUNTAIN SHAVING-BRUSH.

1,141,392.

Specification of Letters Patent. Patented June 1, 1915.

Application filed November 24, 1914 Serial No. 873,684.

To all whom it may concern:

Be it known that we, HENRY A. HEATH and JAMES E. GRAY, citizens of the United States, residing at Urbanna and Saluda, respectively, in the county of Middlesex and State of Virginia, have invented certain new and useful Improvements in Fountain Shaving-Brushes, of which the following is a specification.

This invention relates to brushes and particularly to shaving brushes and the primary object of the invention is to provide a shaving brush having improved means for storing a tube of shaving cream or like semi-liquid or plastic material in the handle of the brush.

A further object of the invention is to provide a brush of the character described so constructed that the shaving cream or like material stored in the handle may be fed into the head or bristles of the brush without handling the cream itself, but by the manipulation of the handle from the outside.

With these objects in view the invention consists in the improved construction, arrangement and combination of the parts of a shaving brush of the character specified, which will be hereinafter fully described and afterward specifically claimed.

In order that the construction and operation thereof may be readily comprehended, we will now proceed to fully describe our invention in connection with the accompanying drawings, which illustrate a preferred embodiment thereof, in which drawings—

Figure 1 represents in elevation a brush constructed in accordance with our invention. Fig. 2 represents a sectional view on a plane cutting centrally and longitudinally through the brush. Fig. 3 represents in perspective the plate or piston for pressing against the tube or other package of cream in order to feed it toward the head of the brush. Fig. 4 represents the interior tube of the brush for containing the tube or package of cream.

Like reference characters mark the same parts whenever they appear in a plurality of the figures of the drawings.

Referring specifically to the drawings, 5 indicates the forward or front end of the body of the brush which is preferably of a cylindrical form provided with a partition or diaphragm 6 in front of which is a chamber to receive the bristles 7, said diaphragm having a central opening 8 from which ex-

tends a tube 9 into the bristles, said tube being provided with an enlarged portion 10 threaded to receive the threaded end of a collapsible tube of cream or the like, such tube affording free passage of the cream through the diaphragm and the inclosed ends of the bristles, into the free, or projecting portions of the bristles.

A chamber 11 is provided in the part 5, 65 inside of the diaphragm, the sides of which chamber are threaded at 12 to receive the threaded end 13 of an inner tube or body 14, the outer end 15 of said inner tube being provided with a knurled head 16 to facilitate the turning of the tube.

The tube 14 is slotted longitudinally as at 17, said slots being of proper outline and position to receive side wings 18, of a plate or piston 20 fitted to slide longitudinally in 75 the tube, said wings being threaded, as at 21, on the outer surfaces and projecting slightly beyond the periphery of the tube to engage interior threads 22 extending from end to end of an outer tube 23 fitted to rotate on 80 the tube 14 and held in position longitudinally on said tube 14 by the end 5 and the knurled or handle end of the tube 14.

With the parts in their positions for use and the head of an ordinary collapsible tube 85 19 of cream, or the like, held in the enlarged threaded portion 10 of the tube 9, and the body of said collapsible tube inclosed in the inner tube with its opposite end resting on the plate or piston 20, the outer tube may 90 be grasped in one hand, (preferably the left hand) and the knurled head 16 turned with the other hand. This will carry the inner tube around in the outer tube, and the engagement of the wings 18 and 19 with the 95 threads 22 of the outer tube will cause the piston or plate 20 to advance toward the bristles or head of the brush, and any desired quantity of the contents of the collapsible tube may thus be squeezed out and 100 through the tube 9 into the bristles of the brush, the amount being dependent upon the extent of the turning of the inner tube.

We have particularly and specifically described the construction, location, and operation of the several parts comprised in the invention, but it will be obvious to those skilled in the art to which the invention most nearly appertains, that slight changes and variations may be made therein without 110 departing from the spirit and scope of the invention as hereinafter claimed.

Having thus fully described our invention, what we claim as new, and desire to secure by Letters Patent of the United States, is

- 5 1. A brush of the character described comprising a cylindrical forward end, bristles in said end, an inner tube communicating through the end with the bristles, a piston in the inner tube, and means, outside of the inner tube and fixed against longitudinal movement, for propelling the piston in the inner tube to force its contents into the bristles.
- 10 2. A brush of the character described comprising a cylindrical forward end, bristles in said end, an inner tube communicating through the end with the bristles, a piston in the inner tube, and a rotatable tube, outside of the inner tube and fixed against longitudinal movement, for propelling the pis-
- 15 3. A brush of the character described comprising a cylindrical forward end, bristles in said end, an inner tube communicating through the end with the bristles, a piston in the inner tube having threaded wings projecting through the slots, and an outer tube encompassing and adapted to rotate on the inner tube and fixed against longitudinal movement, said outer tube having interior threads engaging the threads of the wings.

ton in the inner tube to force its contents into the bristles.

3. A brush of the character described comprising a cylindrical forward end, bristles in said end, an inner tube communicating through the end with the bristles, and provided with longitudinal slots, a piston in the inner tube having threaded wings projecting through the slots, and an outer tube encompassing and adapted to rotate on the inner tube and fixed against longitudinal movement, said outer tube having interior threads engaging the threads of the wings.

In testimony whereof we affix our signatures in presence of two witnesses.

HENRY A. HEATH.
JAMES E. GRAY.
